T. F. CULLINAN

STAKE HOLDER

Filed April 14, 1922

Inventor
Thomas F. Cullinan

Howard E. Bartlow
Attorney

UNITED STATES PATENT OFFICE.

THOMAS F. CULLINAN, OF PROVIDENCE, RHODE ISLAND.

STAKE HOLDER.

Application filed April 14, 1922. Serial No. 552,773.

To all whom it may concern:

Be it known that I, THOMAS F. CULLINAN, a citizen of the United States, residing at Providence, in the county of Providence and 5 State of Rhode Island, have invented certain new and useful Improvements in Stake Holders, of which the following is a specification.

This invention relates to an improved 10 form of stake holding device adapted more particularly to rigidly support stakes located about the edge of a vehicle body, for the purpose of retaining a load in position thereon; and the object of this invention is 15 to provide simple and effective means whereby the stake may be bound and locked firmly into its holder or socket to prevent it from becoming disengaged and lost, and also to prevent the stake from rattling or moving 20 about in its socket.

With these and other objects in view, the invention consists of certain novel features of construction, as will be more fully described, and particularly pointed out in the 25 appended claims.

In the accompanying drawings:

Figure 1 is a perspective view illustrating my improved locking device as applied to a stake holder.

30 Figure 2 is a sectional elevation illustrating my improved locking device as applied to a stake holder.

Figure 3 is a detail showing my improved form of clamp screw in detail.

35 Figure 4 is another form of socket member to which my clamping device is attached.

It is found in practice that wagon stakes in the ordinary socket or holder soon become 40 loose, fall out and are lost, and as such stakes are quite expensive I have found it to be of advantage to provide means for locking them in their sockets so that they cannot accidentally jump out or be too readily withdrawn and so become displaced and lost, and the following is a detailed description of 45 one means by which this result may be accomplished:—

With reference to the drawings, 10 designates my improved socket member which 50 may be provided with flanges 11, or other suitable means by which it may be conveniently attached to the frame 12 of a vehicle, and on the outer surface of the wall of this 55 socket member I have formed a boss or pro-

tuberance 13 drilled and threaded as at 14 to receive a clamp screw, and the inner wall of this socket at this threaded portion is recessed at 15 for the purpose presently described. 60

In order to provide a simple and effective clamping device for the stake 16, I have formed the clamping screw 17 with an enlarged inner or binding head 18 and an outer winged operating head 19 which may be 65 secured to the body of this screw by a pin 20 or other suitable means whereby it may be removed when desired.

This screw is of such a length that it can be passed from the inner portion of the socket outwardly through the threaded opening 14 bringing the inner enlargement 10 on the inside thereof, the winged head 20 being subsequently attached to the outer end. 70

The lower end of this socket member is 75 preferably provided with an inturned flange or finger 25 against which the inner end 21 of the reduced portion 22 of the stake may rest.

In order to provide means in the stake 80 cooperating with the screw 14 to securely retain the stake when positioned in its socket, I have formed a recess 23 in that side of the stake which comes opposite the clamping screw and I have preferably lined 85 this recess with a metal thimble 24, the inner wall of this thimble being tapered as at 25 so as to be engaged by the enlargement 18 on the end of the screw whereby when the screw is forced inwardly it engages this 90 tapered wall and presses the stake downwardly onto the inturned flange 20 thereby securely binding and locking the stake tightly in position in its socket and this tapered wall also serves to clamp and bind 95 the clamp screw in its threaded bearing thereby also serving to prevent it from becoming loosened.

My improved stake locking means is 100 simple and inexpensive in construction and yet very effective in its operation, and by its use the stakes may be securely locked in the body of a vehicle against possibility of their becoming loosened, jumping out and lost. 105

The foregoing description is directed solely towards the construction illustrated, but I desire it to be understood that I reserve the privilege of resorting to all the mechanical changes to which the device is 110

susceptible, the invention being defined and limited only by the terms of the appended claims.

I claim:

5. 1. A stake holder comprising a socket member having means by which it may be attached to a vehicle frame, and a clamp screw threaded through the wall of said socket, in combination with a stake adapted to be positioned in said socket, the same having a locking recess with a tapered wall therein to be engaged by said screw to force the stake downward.
10. 2. A stake holder comprising a socket member having a flange by which it may be readily attached to a vehicle frame, a clamp screw threaded through the wall of said socket, in combination with a stake formed of fibrous material adapted to be positioned in said socket and having a co-operating metal-lined recess formed therein to receive the binding end of said screws.
15. 3. A stake holder comprising a socket member having means by which it may be attached to a vehicle frame, a clamp screw

threaded through the wall of said socket and having an enlargement on its inner end, in combination with a stake of fibrous material adapted to be positioned in said socket having a cooperating metal-lined recess formed therein to receive the binding end of said screw, the inner wall of said socket being recessed to permit said enlargement to be withdrawn thereinto to permit the stake to be freely positioned in and withdrawn from its socket when desired.

35. 4. A stake holder comprising a socket member having means by which it may be attached to a vehicle frame, an inturned stake-supporting lip near the lower end of said socket, and a clamp screw threaded through the wall of said socket, in combination with a stake adapted to be positioned in said socket, the same having a locking recess with a tapered wall therein to be engaged by said screw to force the stake downward against said inturned lip.

40. In testimony whereof I affix my signature.

THOMAS F. CULLINAN.
